UNITED STATES PATENT OFFICE.

LOUIS MORDECAI JAMPEL, OF NEW YORK, N. Y.

DESIGN FOR A SPINNING TOP.

Application filed August 11, 1925. Serial No. 14,395. Term of patent 7 years.

To all whom it may concern:

Be it known that I, LOUIS MORDECAI JAMPEL, a citizen of the United States, residing at New York, in the county of New York and State of New York, and whose post-office address is 86 East 10th Street, New York city, N. Y., have invented a new, original, and ornamental Design for a Spinning Top, of which the

following is a specification, reference being had to the accompanying drawing, forming part thereof.

The figure is a perspective view of a spinning top, showing my new design.

I claim:—

The ornamental design for a spinning top, as shown.

LOUIS MORDECAI JAMPEL.
